COMBINATION EYE GLASS TEMPLE AND HEARING AID

Manfred J. Pollak, 1115 Michigan Ave.,
Evanston, Ill. 60202

Filed May 15, 1967, Ser. No. 7,111

Term of patent 14 years

(Cl. D57—1)

FIG.1

FIG.2

FIG.3

FIG.4

FIG.5

FIG.6

FIGURE 1 is a side elevational view of a combination eye glass temple and hearing aid, showing my new design;

FIGURE 2 is a side elevational view of the opposite side thereof illustrated in FIGURE 1;

FIGURE 3 is a top plan view thereof illustrated in FIGURE 2;

FIGURE 4 is a bottom view thereof illustrated in FIGURE 3;

FIGURE 5 is a rear elevational view thereof as viewed in FIGURE 2; and

FIGURE 6 is a front elevational view thereof as viewed in FIGURE 2.

The broken line showing of the eye glass in FIGURE 1 is for illustrative purposes only.

I claim:

The ornamental design for a combination eye glass temple and hearing aid, as shown and described.
